OBSERVATION BUOY

Serge G. Kotelev and Sophie F. Kotelev,
Long Island City, N. Y.

Application February 26, 1942, Serial No. 432,466

3 Claims. (Cl. 114—4)

Our invention relates to observation buoys and has particular reference to buoys made in the form of hollow sealed vessels adapted to be anchored in a desired position in open waters, near harbors, etc.

Our invention has for its object to provide a hollow buoy so constructed that it can be occupied by a crew of operators and provided with facilities for observing the vicinity of the buoy and reporting to shore stations the presence of enemy ships or airplanes.

We also provide our buoy with a disappearing gun of a suitable caliber, preferably light machine gun, which can be used for defense or attack.

Another object of our invention is to provide means to support the buoy on an anchored chain, means being provided to adjust the length of the chain from the inside of the buoy for moving the buoy from one place to the other. We also provide means to turn the buoy in a desired direction.

Another object of our invention is to provide a buoy with torpedo tubes which can be discharged in a desired direction. We provide for this purpose torpedo tubes at the bottom of the buoy for ordinary automotive torpedoes which can be discharged by compressed air or other suitable agency.

Still another object of our invention is to provide a telescopic periscope and a telescopic observation dome having on top a controlled searchlight.

Our invention is more fully described in the accompanying specification and drawings, in which:

Fig. 1 is a sectional elevational view of our buoy;

Fig. 2 is a sectional detail view of the anchor chain support;

Fig. 3 is a detail view of the anchor;

Fig. 4 is a sectional view taken on the line 4—4 of Fig. 1;

Fig. 5 is a rear view of the buoy;

Fig. 6 is a top plan view of the same.

Our mooring buoy consists of a vessel 1 made of metal and preferably welded to make it air tight, although, of course, it can be made air tight by other suitable methods. The walls of the vessel are lined on the outside with a layer 2 of heat-insulating material, such as plywood, plastic, etc. A drum 3 is rotatively supported on a shaft 4 in brackets 5, 5' at the bottom of the vessel 1 and supports a chain 6 for an anchor 7. The anchor (Figs. 2 and 3) may have four

prongs 7' so that it will grip the bottom in any position. The drum has a worm gear 8 at the side engaged by a worm 9 at the end of a vertical shaft 10 passing into the vessel through a hole in the bottom plate 11 and through an air-tight gland 12 in a false bottom 13 between two tubes 13' for torpedoes 14. The upper end of the shaft 10 has a handwheel 15 which can be turned by an operator 16 for winding the chain on the drum or for unwinding therefrom. A tubular guide 17 for the chain is rotatively supported on the ends of the drum shaft 4 and is moved up or down by the pressure of the chain.

15 The brackets 5, 5' are suspended from an internal gear 18 rotatively mounted on the shaft 10 and engaging a pinion 19 on a stationary shaft 20 whose upper end is fastened to the bottom wall 11, an annular bearing 18' supporting the gear 18. A central gear 21 is in mesh with the pinion 19, being mounted on a tubular shaft 22, concentric with the shaft 10 and having a handwheel 23 at the end.

By turning the wheel 23 it is possible to turn 25 the vessel in any desired direction, the internal gear 18 being held relatively stationary by the tension of the chain. A chair 24 is provided for the operator 16, the chair being preferably mounted on a swivel 25 so that it can be adjusted to a desired position by the operator or moved to avoid excessive inclinations when heavy waves strike the vessel.

The torpedo tubes 13 are closed at the front by cover plates 26 sliding between rails 27 and 35 having racks 28 engaged by pinions 29 on shafts 30 with handwheels 31 inside the vessel.

Sleeping beds 32, 33 are provided in the end portions of the vessels for the operators; also, a movable table 34 and other living facilities.

40 An elevated chair 35 is provided for a second operator 36, the chair being mounted on a telescopic post 37 which may be operated as a hydraulic cylinder, controlled by a pedal 38. The chair is placed inside an opening 39 in the deck 45 40 of the vessel. A transparent cylinder or dome 41 is slidably fitted in the opening 39, a packing gland 42 being provided to render the junction water-tight. The dome 41 is normally held in a raised position, as shown, the bottom flange 43 being held by clamps 44. The chair 35 can be raised to the top of the dome, to enable the operator to observe the surface of the surrounding sea. Radio transmitting and receiving sets 60 and other instru-

ments may be provided at the side of the chair 35 for the operator.

A small searchlight 45 is mounted at the top of the dome with a handle 46 for its rotation. A reflector 47 shields the rear portion of the searchlight. Air vents 48 in the dome may be closed with a valve 49 when the dome is lowered to avoid detection by enemy boats. A small periscope 50 may be then used for observing the enemy's position.

The top deck 40 is also provided with an opening or port 51 forming an entrance into the vessel for the operators. The port is normally closed by a lid, made water-tight by a rubber gasket 52 and tightening clamps 53. The lid is held on a hinge 54 and can be swung into an open position, shown in dotted lines in Fig. 1. A machine gun or similar weapon 55 is mounted on articulated levers 56, 57 under the lid, being normally held in a folded position under the lid, as shown in full lines in Fig. 1, by a strap 58. The gun may be swung into firing position, shown in dotted lines in Fig. 1, when the lid is open. A removable or folding table 59 is placed under the opening for supporting the operator at the gun. The other operator inside the vessel will then help the gunner with the ammunition, etc.

A hook or eye 61 is provided on top of the vessel for raising it out of water by a crane; also a towing hook or eye 62. Low hand rails 63 are placed on top of the vessel; also hooks 64 for a line or cable.

It is understood that our mooring buoy may be further modified without departing from the spirit of the invention, as set forth in the appended claims.

We claim as our invention:

1. An observation buoy comprising a hollow vessel adapted to float in water and having an

opening at the top for admitting a crew of operators into the vessel; a bracket rotatively supported on a vertical axis on the outer side of the bottom portion of the vessel; a flexible member extending from the bracket adapted to be anchored to the bottom of a sea; and means to rotate the bracket from the inside of the vessel thereby rotating the vessel in relation to the flexible member.

10 2. An observation buoy comprising a hollow vessel adapted to float in water and having an opening at the top for admitting a crew of operators into the vessel; means to support and to operate weapons of attack in the vessel; a bracket rotatively supported on the outer side of the vessel; a flexible member extending from the bracket adapted to be anchored to the bottom of a sea; a shaft extending from the bracket into the vessel; and means to manually rotate the shaft thereby rotating the vessel in a horizontal plane for placing the weapons in a desired direction.

3. An observation buoy comprising a hollow vessel adapted to float in water and having an opening at the top for admitting a crew of operators into the vessel; means to support and to operate weapons of attack in the vessel; a bracket rotatively supported on the outer side of the vessel; a spool in the bracket; a flexible member wound on the spool extending from the bracket and adapted to be anchored to the bottom of a sea; a pair of concentric shafts, one of the shafts extending from the bracket into the vessel for rotating the bracket, the other shaft extending into the vessel for rotating the spool with the cable.
